UNITED STATES PATENT OFFICE.

CHARLES H. HORTON, OF WOONSOCKET, RHODE ISLAND, ASSIGNOR TO PERFORATED PAD COMPANY, OF WOONSOCKET, RHODE ISLAND, A CORPORATION OF RHODE ISLAND.

HARNESS SPREADER.

1,413,734.

Specification of Letters Patent. Patented Apr. 25, 1922.

Application filed February 11, 1921. Serial No. 444,190.

To all whom it may concern:

Be it known that I, CHARLES H. HORTON, a citizen of the United States, and resident of Woonsocket, county of Providence, State 5 of Rhode Island, have invented an Improvement in Harness Spreaders, of which the following description, in connection with the accompanying drawing, is a specification, like characters on the drawing representing like parts.

This invention relates to a harness ornament such as employed by teamsters and others to give a pleasing finish to the harness at various points. Such a device comprises a plurality of rings usually of bright 15 contrasting colors arranged in a row and held in place by a suitable connector.

The object of the invention is to provide such a device employing a plurality of rings 20 so constructed that the rings will lie substantially flat against and parallel with the connector. Thus the rings maintain their position and insure the desired pleasing effect.

25 The object of the invention is further to provide a ring, preferably of celluloid for such a harness ornament in which the ring has the shape of an annulus of flat arcuate cross section.

30 Other objects and features of the invention will appear more fully from the accompanying description and drawing and will be particularly pointed out in the claim.

In the drawings:

35 Figure 1 is a plan view of a harness ornament in the form of a spreader embodying a preferred form of the invention.

Figure 2 is a view chiefly in central cross section of the construction shown in Figure 1.

The device comprises a plurality, preferably two, of parallel threaders for supporting and retaining the rings in position. These threaders in the form illustrated are 45 shown as the parallel extending portions of a single strip of flexible material such as a leather strap. In the construction illustrated this leather strap at one end 1 is passed through the ring 2 of a snap hook 3.

50 From the ring 2 the strap extends to form the threader 4 and is conveniently at 5 passed through a finishing ring 6. From the point 5 the strap returns parallel with itself to form the second threader 7 and, 55 when the device is completed is secured to

the end 1. As shown the end 8 of the strap is riveted in place between the end 1 and the body of the threader 4. The snap hook affords a convenient means for attaching the ornament to the harness and the ring 6 may 60 serve as an ornament or as a guide for a rein or other part of the harness.

A plurality of rings are employed and constitute one feature of the invention. These rings may be of the same or of varying size and proportion. Each ring is in the shape of an annulus and the cross section of the annulus as seen in Figure 2 is of a flat arcuate form. These rings are preferably stamped out of celluloid and 70 brightly colored to give the desired ornamental effect. In the construction illustrated the rings 9 adjacent the hook are of comparatively small diameter, the rings 10 of a larger diameter and the rings 11 of a 75 still larger diameter so that a tapered effect is given to the device. These rings may be of any color as, for example, alternating red, white and blue.

Suitable means are provided for clamping together the threaders 4 and 7 at various points. Such means may conveniently take the form of rectangular endless bands 12 slipped over the assembled threaders. These bands may be made of celluloid and 85 colored as desired.

The rings 9, 10 and 11 are arranged so that each ring has a threader extending through it and the clamping bands 12 are located at points each side of the ring where 90 the threader is passed through the ring.

When the device is completely assembled it takes the form shown in the drawing and it will be seen that the clamping bands 12 hold the section of the ring between the 95 clamping bands snugly clamped between the two threaders. Thus the rings are held in general parallelism to the threaders and are restrained by reason of the substantially flat cross section of the rings from being turned 100 out of position. This insures that the rings shall always retain their position substantially as shown in the drawing and thus retain the general pleasing effect produced by the device.

Having thus described my invention, what I claim as new and desire to secure by Letters Patent, is:

A harness ornament comprising a strip of flexible material having its ends con- 110

nected and extended to present parallel
threaders, a plurality of rings having a
substantially flat cross section, each ring
having a threader extending through it, and
5 clamping bands slidingly mounted on the
threaders and clamping together the thread-
ers at points each side of the rings, and

clamping the rings between the threaders
whereby the rings are held in general par-
allelism to the threaders and are restrained 10
against turning out of position.

In testimony whereof, I have signed my
name to this specification.

CHARLES H. HORTON.
